(57) **CLAIM**

The ornamental design for an organizer with drawer as shown and described.

DESCRIPTION

FIG. 1 is a top perspective view of an organizer with drawer showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof;

FIG. 8 an exploded top perspective view thereof;

FIG. 9 is an exploded bottom perspective thereof; and,

FIG. 10 is a top perspective view shown within an environment of use.

The broken lines immediately adjacent to the shaded areas depict the bounds of the claimed design, while all other broken lines are directed to environment. The broken lines form no part of the claimed design.

1 Claim, 10 Drawing Sheets
